WHEEL DRESSING MECHANISM

James G. Harper and Cecil W. Hopkins, Waynesboro, Pa., assignors to Landis Machine Company, Waynesboro, Pa., a corporation of Pennsylvania.

Application April 6, 1944, Serial No. 529,810

6 Claims. (Cl. 125—11)

1

This invention relates to wheel dressing mechanism and more particularly to a mechanism of that type which is employed in thread grinding machines for the purpose of dressing or truing the profile of the abrasive thread grinding wheel.

It is one of the objects of our present invention to provide a dressing or truing mechanism having certain novel features of construction which may be used to advantage in either the automatic or hand operated type of dressing mechanism.

It is another object of the invention to provide improved means for controlling the movements of the dressing tool carrying slide in parallel relation with the grinding wheel axis and also perpendicularly thereto, whereby a rapid and accurate dressing or truing of the wheel profile is obtained.

It is an additional object of our invention to provide a novel mounting and arrangement of the tool slide and the carriage for substantially frictionless relative movement in angularly related planes and with greater stability and accurate control of the movement of the wheel dressing tool.

A still further object of our invention is to provide a wheel dressing mechanism in which the several parts are of simple structural form and are cooperatively associated in a compact organization sealed within a housing of minimum dimensions.

Among the subordinate objects of our invention are the provision of a simple and positively operating means for the tool slide carriage, a novel mounting and arrangement of the template and stylus with respect to the tool slide for controlling the perpendicular movement thereof with respect to the wheel axis, and means for adjustably mounting the wheel dressing unit upon the dresser slide of a grinding machine for bodily movement therewith to and from operative relation with the grinding wheel.

Other practically important features of our present invention will become evident from the following detailed description of the several practical embodiments thereof illustrated in the accompanying drawings, in which similar reference characters designate corresponding parts throughout the several views, and wherein:

Figure 1 is a horizontal sectional view taken substantially on the line 1—1 of Figure 2, illustrating an automatic type of our improved wheel dressing mechanism;

Figure 2 is a transverse vertical section taken substantially on the line 2—2 of Figure 1;

Figure 3 is a longitudinal vertical section, taken substantially on the line 3—3 of Figure 1;

2

Figure 4 is a transverse sectional view taken substantially on the line 4—4 of Figure 1;

Figure 5 is a horizontal sectional view, taken substantially on the line 5—5 of Figure 3;

Figure 6 is a detail plan view, certain parts thereof being shown in section;

Figure 7 is a horizontal sectional view, taken substantially on the line 7—7 of Figure 9, the latter view being placed 90° out of true position, and illustrating a manually operable embodiment of our invention;

Figure 8 is a vertical sectional view, taken substantially on the line 8—8 of Figure 7;

Figure 9 is a similar sectional view taken substantially on the line 9—9 of Figure 7; and

Figure 10 is a detail vertical section, taken substantially on the line 10—10 of Figure 7.

With further reference to the drawings, and for the present more particularly to Figures 1 to 6 thereof, we have therein illustrated a typical structural example of the novel features of our present invention as embodied in an automatic type of wheel dressing mechanism. As therein shown, the several cooperatively related parts of this mechanism are enclosed within a substantially rectangular housing, comprising the body 10, opposite ends of which are closed by the cover plates 11 and 12, respectively, detachably secured to the body wall by the bolts or screws 13 and 14, respectively. The top of this housing is similarly closed by the cover plate 15 detachably secured to the housing wall by the screws 16.

The bottom wall of the housing body 10 internally thereof is rabbeted along opposite sides 35 thereof, as at 17, to provide seats for the longitudinal guide members, 18 and 19, respectively, which are substantially coextensive with the internal longitudinal dimension of the housing. The guide member 18 is rigidly secured to the

40 housing wall by a plurality of screws 20. The other guide member 19 is slidably held upon its seat 17 by the screws 21 extending through elongated openings 22 in the bottom wall of the housing body. Thus, it will be understood that this member 19 may have limited movement with respect to the member 18 transversely of the housing.

Between the guide members 18 and 19 the tool slide carriage 23 is positioned. Intermediate of its opposite ends this carriage is cut away or recessed, as at 24, for a purpose to be later described, said recess opening upon one longitudinal edge of the carriage plate which is opposed to the guide member 19. The inner side faces of the 50 guide members 18 and 19 and the opposed edge

faces of the carriage plate 23 are longitudinally grooved as at 25 and 26, respectively. These grooves provide race-ways for the anti-friction balls 27 held in spaced apart relation by the retainer 28 between member 18 and the carriage. Similar anti-friction balls 29 and retainers 30 are interposed between the other guide member 19 and the carriage 23 at each side of the recess 24 in the carriage plate. These anti-friction bearing units provide adequate supports, sustaining the carriage plate 23 with respect to the housing wall and guide members 18 and 19 for substantially frictionless movement longitudinally of the housing. Longitudinal movement of the retainers 28 and 30 is restricted and limited by the stop pins 31 suitably embedded in the guide members 18 and 19.

The guide member 19 is provided with longitudinally spaced recesses 32 opening on the outer side face thereof and springs 33 in these recesses, bearing against a side wall of the housing, constantly urge the member 19 and carriage plate 23 transversely toward the member 18, thus insuring proper automatic adjustment to compensate for wear.

The carriage plate 23 is provided with a longitudinally extending bore 34 in which the coiled spring 35 is received. One end of this spring has bearing engagement with a cylindrical pin 36 slidably engaged in one end of the bore 34 and having a convex outer end in bearing contact with the end closure or cover member 11 of the housing. A tension adjusting screw 37 for said spring is threaded in the other end of the bore 34. It will therefore be understood that the spring 35 yieldingly urges the carriage plate 23 longitudinally in one direction with respect to the guide members 18 and 19.

A vertically disposed bushing 38 is suitably secured in the dresser slide of the grinding machine, which is partially illustrated at 39 in Figure 3 of the drawings. The upper end of said bushing is received in the opening 38' in the bottom wall of the housing 10. A shaft 40 journaled in the bushing 38 has a reduced upper end portion 41 to which the pinion 42 is keyed or pinned as at 43. This pinion is located in the recess 24 of the carriage 23, and at its upper end is constantly engaged with the teeth of a rack 44 secured by screws 45 in a recess 46 in the upper face of the carriage plate 23. Back lash or lost motion between the teeth of pinion 42 and rack 44 is eliminated by the action of the spring 35. Longitudinal movement of the carriage 23 in each direction is limited by the stop pins 47 suitably fixed in the bottom wall of the housing.

While any suitable means may be provided for automatically imparting oscillatory rotary motion to the shaft 40 and pinion 42 in the operation of the thread grinding machine, for this purpose we provide the simple arrangement shown in Figures 3 and 5 of the drawings in which the lower end of the shaft 40 is secured to one end of a lever 47' having a longitudinal guide channel 48 for the roller 49 mounted on the end of a crank arm 50 secured to the power driven shaft 51. It will be obvious that, in the rotation of shaft 51 and the crank 50, oscillatory motion is transmitted to the pinion 42 so that the carriage 23 will be alternately moved longitudinally within the housing 10 in opposite directions. These movements of the carriage are limited by the pins 47 contacting the sides of the recess 24 in the carriage 23.

Upon the upper face of the carriage plate 23 an L-shaped bracket 52 is rigidly mounted.

The horizontal flange of this bracket is provided on its lower face with a longitudinal rectangular rib 53 engaged in a transverse groove 54 formed in the upper face of the carriage plate and accurately locates the vertical flange of said bracket transversely of the carriage in fixed relation to one side edge of the recess 24 in said carriage. The horizontal bracket flange is rigidly secured to the carriage plate by a plurality of screws as indicated at 55.

To one side of the vertical flange of bracket 52 at the upper end thereof the guide member 56 is secured by screws 57. The tool carrying slide 58 is positioned in a vertical plane between this guide member and the carriage plate 23, upper and lower anti-friction balls 59 and 60, respectively, held in the retainers 61 and 62, being interposed between said slide and the member 56 and carriage plate 23. Longitudinal movement of the ball retainer 61 is limited by the stop pins 63 fixed in the member 56 and slide 58 and longitudinal movement of the retainer 62 is limited by the stop pins 64 fixed in the tool slide.

A pin 65 is fixed to the tool slide 58 and projects transversely therefrom into the slot 66 in bracket 52. This projecting end of the pin has a flat side face 67 to which one end of a guide rod 68 is fixed. This rod extends in parallel relation to the slide 58 into a bore 69 in the bracket which communicates at one end with slot 66. A spring 70 surrounding rod 68 bears at one of its ends against the face 67 of pin 65 and at its other end against the tension adjusting screw 71 threaded in the outer end of bore 69. It will thus be understood that the spring 70 yieldingly resists transverse movement of the tool slide 58 in one direction with respect to the carriage plate 23 and urges said tool slide toward the periphery of the grinding wheel, indicated at 72.

To the inner face of the rear wall of housing 10, above the member 18, a bracket 73 is rigidly attached, as by screws 74. The horizontal arm 75 of this bracket has a recessed upper face 76 to which is rigidly secured the template bar 77 extending from said bracket longitudinally of the carriage 23 and into a slot or recess 79 in the inner or rear end of the tool slide 58. This end of the template bar is formed with a replica 80 of the profile outline to be produced upon the peripheral face of the grinding wheel 72, which in the present instance is represented by a thread outline of Whitworth form. A stylus 81, secured to the rear end of the slide 58 by screw 82, also extends into the recess 79 and is constantly urged into cooperative engagement with the part 80 of the template bar by the action of the spring 70.

The outer end of the tool slide 58 is movable through an opening 82 in the side wall of the housing 10 and is formed with a reduced neck portion 83 upon which the dressing tool holder 84 is detachably mounted. Preferably, this holder has a groove 85 to receive the rib 83' on the end face of the neck 83 to prevent pivotal movement of the holder with respect to the attaching screw 86. The wheel dressing tool 87 is detachably secured in holder 84 in conventional manner by means of the screw 88. The opening 82 in the housing wall is completely closed and sealed by means of a flexible diaphragm 89 of leather or other suitable material. An air and dust tight connection between the outer edge portion of this diaphragm and the housing wall is effected by means of the clamping ring 90 and screws 91 which are threaded into the wall of

the housing and detachably secure the diaphragm thereto. The neck 83 of slide 58 is provided with the groove 92 to receive the inner edge of the diaphragm 82 which is securely held in airtight engagement with the walls of said groove by the clamping ring 93. Thus, it will be seen that the interior of the housing 10 and all parts of the mechanism contained therein to control movement of the tool 84 are completely sealed so that grinding wheel dust or other foreign matter cannot find its way to the interior of the housing and impair the proper and accurate functional operation of said mechanism.

Referring again to Figure 3 of the drawings we preferably mount the wheel dressing unit upon the dresser slide 39 for bodily adjustment relative to said slide so that the paths of movement of the carriage 23 and tool slide 58 may be accurately related to the plane of rotation of the grinding wheel 72. To this end, a bracket member 94 is fixed to the under side of the housing 10 at one end thereof by the screws 95 and is formed with a slot 96 to receive the projecting end of a pin 97 fixed in the end of the slide 39. Aligned relatively adjustable screws 98 are threaded in the bracket 94 and bear against the projecting end of pin 97 at diametrically opposite points. By properly adjusting these screws 98, the housing 10 and the entire dressing mechanism may be pivotally moved about the axis of pinion 42 to position the path of reciprocating motion of carriage 23 in accurate parallel relation with the rotative axis of the grinding wheel 72 and the slide 58 in exact perpendicular relation to said axis.

In the operation of the mechanism above described, it will be apparent that, in the rotation of the crank 50, pinion 42, coacting with the rack 44 in its oscillating motion, will reciprocate the carriage plate 23 in a direction parallel to the axis of the grinding wheel 72, and the tool slide 58 will be similarly moved as a unit with said carriage. As the dressing tool 87 is thus moved across the face of the grinding wheel 72, stylus 81 fixed to slide 58 is moved in contact with the thread outline 80 of the template bar 77 fixed to the stationary bracket number 73, and, in conjunction with the action of spring 70, produces independent reciprocatory movement of the tool slide 58 transversely across the carriage 23, simultaneously with the movement of said carriage, and in a direction perpendicular to the axis of the grinding wheel 72. Such compound movements of the dressing tool reproduce the outline contour of part 80 of the template bar upon the peripheral face of the grinding wheel.

It is to be particularly observed that we provide anti-friction supporting means for the tool slide extending entirely across the carriage plate 23. Thus, maximum stability in the mounting of said tool slide is obtained and all possibility of angular displacement thereof relative to the carriage, which would result in an inaccurate dressing operation of the tool 87, is precluded. In other words, the stylus 81 on the tool slide 58 is at all times in accurate alignment with the outline of the template part 80 in the movement of the carriage plate 23. It will further be appreciated that our invention provides a wheel dressing mechanism of this kind comprising a very compact assembly of a minimum number of mechanical parts of simple structural form, cooperatively associated for accurate func-

tional operation within an enclosing housing of minimum dimensions.

We have also embodied certain of the novel features above described in a manually operable type of wheel dressing mechanism which will now be described, with reference to Figures 7 to 10 of the drawings.

In one practical embodiment of this form of our invention, the dresser mechanism is mounted upon a supporting member 100, suitably fixed to a vertically disposed stationary member of a thread grinding machine (not shown). This support 100 is provided on one side thereof with the male part 101 of a conventional dovetail slide assembly to coact with the female part 103 of said assembly formed on the slide 102. Between one of the inclined faces of the part 101 and the opposing inclined face of the slide 102 the gib 104 is retained in position and tightened against the part 101, as wear may necessitate, by means of the set screws 105. Rotational displacement of these screws from adjusted position is prevented by the locking screws 106 also threaded in the slide 102. Thus movement of the slide 102 is constrained to a direction which is exactly perpendicular to the axis of the grinding wheel 107, shown in Figure 7.

In the end of the support 100, remote from the wheel 107, a bearing 108 is provided for an adjusting screw or shaft 109. This shaft has a threaded section 110 on which the traveling nut 111 is movable. A collar 112 fixed to the shaft 109 by pin 113 has bearing engagement against the inner side of the shaft bearing 108 and a hand wheel 114 secured to the outer end of said shaft in rotative contact with the outer face of the bearing 108, by means of a nut 115, is held against rotative movement on the shaft by the key 116 fixed to said shaft and engaged in the groove 117 of said hand wheel. This hand wheel is provided with a duct 118 through which lubricating oil may be supplied to the bearing 108, the outer end of the duct being normally closed by the screw 119.

The nut 111 is formed with a lug or projection 120 on one side thereof closely fitting within an opening 121 in the slide 102. The nut 111 is also provided with a transverse opening 122 which extends through the projection 120 to receive the screw 123, the enlarged head of which has bearing engagement on the internal shoulder 124 of the projection 120, the threaded shank of said screw extending through the opening 121 in the slide to secure a part of the mounting for the dressing mechanism in attached position on the face of the slide, as will presently be described. It will thus be seen that rotation of the hand wheel 114 will rotate shaft 109 and cause the nut 111 and slide 102 to move relative to the support 100 in a direction perpendicular to the axis of the grinding wheel 107.

Upon the peripheral face of the wheel 114 suitable scale graduations 125 are delineated to cooperate with an index mark 127 on the end face of a pin 126 fixed in the bearing 108. Thus, the necessary degree of rotation of the wheel 114 for a predetermined linear movement of the slide 102 can be accurately gauged.

To the outer side face of the slide 102, laterally spaced apart housing and guiding members 128 and 129, respectively, are attached. The member 128 is rigidly secured to the slide by means of the screws 130, while the screw 123 serves as a common means for attaching the other of said guide members 129 and the nut 111 to slide 102.

A quadrant-shaped part 131 is secured in a recess 133 in the housing member 129 and is preferably symmetrical in external contour with member 129, as shown in Figure 9. The part 131 is formed with a longitudinal recess 134 to receive the template bar 135 which is rigidly fixed to the member 129 by the screws 136.

The members 128 and 129 are assembled upon the slide 102 with their opposed faces in accurately mating contact with each other by the tongue or rib 137 on the member 129 fitting within the groove 138 formed in the opposing face of the member 128. Thus, oppositely inclined guiding surfaces 139 and 140, respectively, for the tool slide carriage, to be presently described, are accurately located relative to each other.

The tool slide carriage includes an elongated part 142 of substantially rectangular form in cross section, the respective faces of which have sliding contact with the guiding surfaces 139 and 140 of the supporting and housing members 128 and 129. The recess 143 formed in the face of the slide 102 constitutes an extension of these guiding surfaces. The outer end of the slideable part 142 of the carriage is integrally formed with a housing member 144 for the tool carrying slide 145, the members 146 and 147, detachably secured to the member 144 in any suitable manner, completing the housing structure.

The part 142 of the carriage is provided with a central longitudinal bore 148 and a tension spring 149 within this bore has one of its ends connected to a pin 150 seated at its ends in notches or recesses 151 in the housing member 144.

The other end of this spring extends through an opening 152 in the slide 102 and is secured to the pin 153, the ends of which are seated in notches or recesses 154 in the rear face of the slide. It will be evident that the spring 149 yieldingly urges the carriage slide 142 inwardly between the members 128 and 129 toward the slide 102 to a normal position.

The rectangular carriage slide 142, at the juncture of two adjacent side faces thereof, is formed with a recess 142' and a plurality of rack teeth 154 on the base wall thereof, have cooperative engagement with the teeth of a pinion 155, formed upon or fixed to the shaft 156, journaled at one of its ends in the vertical bore 157 formed in the guide member 128. This shaft is rotatably supported in the bushing 158 having a driving fit within the opposite end of the bore 157. The inner end of this bushing abuts one end of the pinion 155 and the other end of said bushing is diametrically enlarged to provide a shoulder 159 having abutting contact against the face of the member 128. The end of the shaft 156 extends beyond the bushing 158 and has a collar 160 pinned thereto by the taper pin 161 formed on the end of the shaft operating handle 162. The inner end of the collar 160 has a cylindrical recess 163 to receive the enlarged end of the bushing 158, the wall of this recess extending over and covering the felt ring or other sealing material 164 contained in the peripheral groove 165 formed in the enlarged outer end of the bushing 158. Thus leakage of lubricant contained within the mechanism will be prevented.

As shown in Figure 8 of the drawings, guide members 166 and 167 are secured to the carriage part 144 above and below the slide 145 by suitable screws 168, and also constitute parts of the housing structure which completely encloses the slide with the exception of the reduced forward end 169 thereof which projects through opening 170.

in housing part 144 and carries the dressing tool 171. This tool is detachably fixed to the slide by collar 172 surrounding the said slide and carrying a set screw 173 to engage the shank of the tool 171 and immovably fix the same against the wall of recess 174 in the slide.

In order to exclude grit and dust from the slide housing, a sealing member 175 of any suitable material may be attached to the housing part 144 in closely contacting relation with surfaces of the slide end 169 at the opening 170.

Members 166 and 167 and slide 145 are grooved to receive the rolling elements of anti-friction units 167, similar to those shown in Figure 2 of the drawings.

The carriage part 144 rearwardly of the slide 142 is provided with an opening 171 through which the template bar 135 fixed to the member 129 extends. The rear end of the tool slide 145 is recessed, as at 178, to receive the end of the template bar. In this case the outline part 179 of the template, corresponding to the part 80 in Figure 6, is detachably secured to the template bar by means of a set screw 180.

The stylus 181 which cooperates with the outline part 179 is fixed to the rear end of the tool slide 145 by means of the collar 182 and set screw 183. The slide 145 is also provided with a pin 184 longitudinally extending rearwardly therefrom and slidably supported in the end of a tubular member 183' which is suitably fixed to the housing cover member 146. A spring 185 is interposed between the pin 184 and the tension regulating screw 186 which is threaded in the outer end of the tubular member 183. This spring exerts a light sensitive pressure force against the rear end of the slide to maintain the stylus 181 in operative contact with the outline part 179 carried by template bar 135.

For the purpose of excluding the entrance of grinding wheel dust and other foreign matter, we preferably attach the edges of a flexible boot or a diaphragm 187 in sealing engagement with the members 128 and 129 and the part 144 of the tool slide housing.

From the above description the construction and operation of this manually operable type of our invention will be readily understood. Upon rotation of the wheel or knob 114, the slide 102 with the dresser mechanism mounted thereon is moved as a unit on the support 100 to position the dressing tool 171 in operative relation to the periphery of the grinding wheel 170. The handle or lever 162 is then manually operated to oscillate pinion 155. This pinion cooperating with rack teeth 154 moves the tool slide carriage relative to the fixed parts 128 and 129 and template bar 135 in one direction against the resistance of spring 149, to cause the dressing tool 171 to traverse the profile of the grinding wheel 107 in a path parallel to axis of said wheel. Simultaneously with this movement of the slide carriage, the stylus 181 coacts with the relatively fixed thread outline part 179 and moves the dressing tool 171 perpendicularly of the grinding wheel axis to accurately reproduce said outline form upon the profile of the grinding wheel.

It will be observed that the fundamental features of our invention may be embodied in either the automatic or hand operated type of wheel dressing mechanism in a very compact, space-conserving assembly to operate with maximum efficiency and accuracy in the reproduction of a thread profile of desired outline form upon the periphery of the grinding wheel. In either case

the mechanism embodies a minimum number of parts of simple and durable structural form which are capable of easy and quick assembly in functionally cooperative relation. It is also to be noted that, unlike prior mechanisms of this kind, the stylus and template outline with which it cooperates are completely enclosed within the tool slide housing so that the accumulation of foreign matter on these parts cannot impair the accurate operation of the wheel dressing tool. The embodiment of our invention disclosed in Figures 1 to 6 of the drawings provide an automatic wheel dressing unit of minimum overall dimension which may be mounted on the dresser slide of a grinding machine in the manner above explained to position the dressing tool in accordance with the helix angle of the thread grinding wheel so that said tool will properly and accurately dress the wheel profile.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In wheel dressing mechanism, a housing, a tool slide carriage, means for mounting said carriage within the housing for reciprocating motion longitudinally of the housing, a bracket transversely positioned within the housing on one end of the carriage and fixed thereto, guide means on the bracket spaced from and extending transversely across the carriage, a tool carrying slide, and anti-friction bearing units between said slide and the carriage and guide means, supporting said slide for reciprocating movement on the carriage in a path substantially at right angles to the path of reciprocation of said carriage.

2. Wheel dressing mechanism defined in claim 1, and a stylus carried by said slide, a stationary template mounted in the housing, a pin fixed to the slide, and spring means mounted on said bracket coacting with said pin to yieldingly urge said stylus into coacting engagement with the template.

3. The wheel dressing mechanism defined in claim 1, and a wheel dressing tool fixed to one end of said slide exteriorly of the housing, the

other end of said slide having a recess, a stationary bar mounted in the housing extending longitudinally above the carriage and having a template part at one end positioned in said recess of the slide, and a stylus carried by the slide and coacting with said template part.

4. In combination with the dresser slide of a grinding machine, wheel dressing mechanism mounted thereon for movement to and from operative position with respect to a grinding wheel, said mechanism including a housing, a tool carrying slide and actuating means in the housing to impart a compound movement to said slide in paths substantially at right angles to each other, and manually adjustable means on the housing coacting with means on the dresser slide, to adjustably position the housing, tool slide and slide actuating means relative to the dresser slide, and initially position the dressing tool with respect to the peripheral profile of a grinding wheel.

5. In a wheel dressing mechanism, a rectangular housing, a carriage plate of substantially uniform thickness mounted within said housing on the bottom wall thereof for reciprocating motion in a plane substantially parallel with said housing wall, an actuating member journaled in the bottom wall of the housing and means operatively connecting said member with the carriage to reciprocate the latter, a tool slide, means extending across the upper surface of the carriage plate and directly supporting the tool slide thereon in a plane normal to the path of movement of the carriage, and means for reciprocating the tool slide in said plane, including coacting parts fixed respectively to said tool slide and housing.

6. The wheel dressing mechanism defined in claim 5, in which a bracket is fixed to the carriage plate and anti-friction guide means is interposed between said bracket and the tool slide.

JAMES G. HARPER.
